Primary Examiner — Sanjeev Paul(74) *Attorney, Agent, or Firm* — Thomas P. O'Connell;
O'Connell Law Firm(57) **CLAIM**

The ornamental design for lenses for eyewear, as shown and described.

DESCRIPTION

FIG. 1 is a perspective view of lenses for eyewear showing my new design in use in a frame;

FIG. 2 is a perspective view of the lenses for eyewear;

FIG. 3 is a view in front elevation thereof;

FIG. 4 is a view in rear elevation thereof;

FIG. 5 is a view in left side elevation thereof;

FIG. 6 is a view in right side elevation thereof;

FIG. 7 is a top plan view thereof; and,

FIG. 8 is a bottom plan view thereof.

The broken lines in the drawings represent unclaimed structure that forms no part of the claimed design. Diagonal hatching is used to indicate transparency or translucency of the lenses for eyewear and not surface ornamentation. The dot-dash lines represent the border between claimed and unclaimed subject matter and form no part of the claimed design.
